MANUFACTURE OF TEMPLE ROLL

Charles Thomas Dickey, Elizabeth, N. J.

Application December 12, 1939, Serial No. 308,814

5 Claims. (Cl. 139—296)

This invention relates to a roll for use in a loom temple.

As is well known to those skilled in the art, a loom temple is normally employed at each side of the loom adjacent the fell of the cloth being woven for the purpose of uniformly maintaining the cloth stretched widthwise.

In connection with various types of fabrics, for example, those composed wholly or largely of rayon or cellulose ester filaments as acetated cellulose, or those of a fine and delicate nature, it has long been customary to use rubber or rubber composition as the surface of the roll which engages the cloth. Rubber has many disadvantages, as has pasteboard, wood shavings and the like.

The ideal temple roll according to my researches, is closely approached, where a suitable bonding, agglutinating or matrix material is used as a portion of the temple roll, and has embedded therein a multiplicity of outwardly-projecting fixed fiber or fiber-like ends, to which the frictional-gripping capacity is primarily due; that is, wherein the friction results mainly from a plurality of frayed fibrous ends immovably embedded, contacting the delicate filaments or filaments constituting the goods being processed.

This invention is related to my application for "Temple roll," filed March 25, 1939, as Serial Number 264,065, which in turn, is a continuation in part of my co-pending application Serial Number 249,207, filed January 4, 1939, for "Temple roll and process of manufacture," and is related to my applications, Serial Numbers 283,174, filed July 7, 1939; 277,608, filed June 6, 1939; Serial Number 307,611, filed December 5, 1939; and 308,815, filed December 12, 1939, all for Temple roll.

One of the objects of the present invention is to provide a construction of that type of temple roll employing a non-rubber body, in which the disadvantages inherent in the present types of temple roll are substantially non-existent, as will be more particularly pointed out herein.

Another object is to provide a temple roll having the initial desired frictional gripping surface, which remains uniform and substantially unimpaired for an indefinite period of times.

A third object is to provide a temple roll of required frictional gripping surface which is unacted upon and unimpaired to an observable degree or extent by any of the components of, in, or evolved incident to contact of textile with temple roll.

Another object is the employment of an ag-

glutinating, compacting, or bonding medium of such rigidity, that the inner portion of the filament or fibers, having outwardly-projecting ends, is immovable.

A further object is to provide a temple roll wherein the surface passing in contact with the cloth, does not leave a mark or streak, or deposit material on the goods as is the case where a rubber roll is used, or a roll having a rubber face, especially when the rubber has been softened by the "fumes" from the filaments being woven.

This is an important point, because the goods are usually plain woven white and afterwards dyed. Even if an almost unnoticeable streak is left on the goods from deposition of tiny traces of rubber or rubber substitute, this materially interferes with uniform penetration of dyestuff in the dyeing operation, for the reason that rubber is absolutely insoluble in water, causing uneven and unlevel dyeings to result.

Other objects of the invention will appear more fully and clearly from the accompanying description and drawings, and will be particularly pointed out in the claims.

The general nature, function and purpose of a loom temple of the roll type are so well known and familiar to those skilled in the art, that it here only becomes necessary to illustrate a portion of one typical form of a temple, together with preferred forms of the invention embodied therein.

In the drawings and illustrative examples are shown and described preferred forms of temple roll embodying my invention.

Fig. 1 is a side elevation of a temple head with the form of roll embodying the invention located therein.

Fig. 2 is a plan view of the temple head shown in Fig. 1.

Fig. 3 is a greatly enlarged longitudinal section in perspective of a ribbon of material used in the fabrication of the temple roll.

Fig. 4 is a perspective view of a slab formed by a plurality of the ribbons shown in Fig. 3 as they are prepared for a further step in the fabrication of the temple roll.

Fig. 5 is a perspective view of one strip as cut from the slab of ribbons shown in Fig. 4, and which is used with a second strip to form a temple roll.

Fig. 6 is a perspective view of a core used to form the central portion of a temple roll.

Fig. 7 is a longitudinal section in perspective of a die with the core and strips of which a temple

roll is to be formed, shown therein previous to the closing of the die.

Fig. 8 is an enlarged transverse section taken on the line 8—8 of Fig. 7.

5 Fig. 9 is similar to Fig. 8, but shows the die in closed position as it completes the formation of the temple roll.

Fig. 10 is a side elevation partly in section of the completed temple roll as it is recovered from 10 the die and the mandrel removed.

Fig. 11 is an enlarged section on line 11—11 of Fig. 10.

Fig. 12 is a greatly enlarged section of a portion of Fig. 10.

15 The invention is shown in connection with the usual type of temple wherein two rolls are rotatively mounted. The temples are arranged in pairs, one at each side of the loom, and may be termed right-handed and left-handed since their 20 function is to laterally stretch the cloth being woven to the right and left side of the loom.

The construction of the temple roll is the same in both cases, and therefore only a right-handed temple roll has been illustrated.

25 The form of roll embodied in the present invention is adapted for use in substantially all types of roll temples.

The temple illustrated in Figures 1 and 2 comprises an arm 1, of which only a portion is shown, 30 and by which it is mounted upon the loom at the forward end, and a main body portion or pod 2 formed thereon having a trough-like shape in which the rolls are mounted.

35 The temple rolls are journaled on pins 3 supported in the end walls of the pod 2, the inner ends 4 being fitted into the end wall 5 and the outer ends being provided with enlarged screw-threaded heads 6 which are tightly threaded into the end wall 7.

40 The temple roll 8, to perform its function of putting lateral tension on the cloth being woven, has its surface formed into alternating ridges 9 and grooves 10, arranged in the form of a helix.

The outer part of the roll 8 in which the ridges 45 9 and grooves 10 are later formed, is fabricated or built up so as to produce a multiplicity of frictional-gripping, outwardly-projecting fibers or fiber ends.

50 The formation of the temple roll 8 into the form illustrated contemplates certain novel steps in the utilization of the material from which the roll is made, whereby a substantially complete elimination of waste is attained.

55 Thus a ribbon 11 is prepared which may consist of canvas or other textile 12 of desired weight per unit area, or similar material, which has been treated, impregnated or there has been calendered on a substance 13 of an agglutinating or adhesive nature, neutral in reaction, so as to present exposed faces which are substantially smooth and cut edges wherein the embedded fabric 12 is exposed.

60 The width of the ribbon 11 may be such as to provide sufficient material to form one-half of the circumferential dimension of the completed roll 8, although it is to be understood that other widths may be employed if desired. The length and thickness of the ribbon 11 may vary within wide limits and has no relation to the dimensions 70 of the temple roll 8.

75 The next step in the preparation of the material for forming the roll 8 consists in providing a slab 14 from which strips 16 may be cut for use in the final step of the fabrication of the roll.

The formation of the slab 14 may be accomplished

in a number of ways, but preferably consists in coating, as by a calendering operation, one or both faces of the ribbon 11 with a comparatively thin layer of adhesive, either as a single application or as a plurality of similar or dissimilar coats, the adhesive 15 being of a suitable nature, as a plastic cement or cementitious material, and then selecting the desired number of ribbons 11 of any convenient length and width and causing them to adhere together in parallel relation, face 10 to face.

Instead of coating or impregnating the individual ribbons, the canvas, textile or fabric may be coated, impregnated or calendered with the adhesive in widths and lengths in a manner 15 somewhat similar to that employed in the production of pyroxylin-containing artificial leathers, and the coated fabric may then be cut into strips of width and length desired.

The number of ribbons 11 selected for making the slab 14 must be such that the width of the slab 14 represents the length of the completed roll 8. After the slab 14 has been formed into a firm unit by the application of sufficient pressure, or by heat and pressure, to permit the adhesive 15 25 to cause all the ribbons 11 to adhere to each other, the width of the slab 14 represents the length of the temple roll 8 and the thickness represents substantially one-half of the circumferential dimension of the completed roll. 30

The slab 14 is then cut into a plurality of strips 16 as by a slicing operation along lines a, which cuts are so spaced that the thickness of the strip 16 provides sufficient material of the particular kind selected to form the wall thickness of the 35 temple roll 8.

In Fig. 6 there is shown a detail of a core 20 around which the temple roll 8 is formed, and which provides the journal in which the pins 3 of the temple head is inserted. The core 20 is 40 provided with an aperture 21 and a plurality of longitudinally extending fins or projections 22, shown herein as four.

The next step in the formation of the temple roll 8 consists in utilizing a split die consisting 45 of an upper die 24 and a lower die 25, each die having an internal configuration of nature as desired, and which when placed together, comprise a helix consisting of spaced ridges 26 and grooves 27. Guide pins 28, mounted in the lower die 25 and projecting through apertures in the upper die 24 serve to properly guide and align the two dies, whereby their function may be accurately carried out.

One method of forming the temple roll 8 about 50 the core 20 is as follows: a mandrel 23 substantially longer than the core 20, is inserted in the aperture 21 thereof, and two of the strips 16 then placed on the core 20 in longitudinal relation thereto and on opposite sides thereof and adjacent to two of the fins 22.

The core 20 and strips 16 are then placed with 55 in the open dies 24, 25 in properly aligned position and the dies then submitted to a high pressure, or pressure and heat to close them. The 60 amount and degree of heat required, if heat be used in addition to pressure, will depend upon the thermoplasticity and other physical characteristics of the cementing or bonding medium employed to produce a homogeneous-appearing final 70 product.

The strips 16 are thus forced to, first encircle the core 20, then to impress themselves into the grooves 27 and ridges 26 in the dies, and the fins 22 are at the same time forced into sub- 75

stance forming the strips 16. In place of fins shown, the exterior surface of core 20 may be roughened or have inequalities therein to form anchorages, if it is desired to anchor the fabric 5 and agglutinant to the core 20 to the maximum of adhesion.

When the dies 24 and 25 meet along their split line, it is obvious that the two strips 16 are so compressed as to form a unit which is securely 10 fastened upon the core 20 and has the size and shape of the desired temple roll 8. A sufficient quantity of bonding material 15, originally applied to the ribbons 11, is exuded during the application of pressure or heat and pressure to the 15 dies so that the adjacent edges of 16 are, as they meet, caused to bond and firmly adhere each to the other, forming a substantially invisible line, thus completing the formation of the roll 8 as a unit.

20 The function of the mandrel 23 during the application of pressure, or heat and pressure, to the dies is to prevent collapse or distortion of the core 20.

After the dies have completed their function 25 they are opened and the completed temple roll 8 recovered. The mandrel 23 is then removed and the temple roll 8 is ready to be assembled in the temple head 2 as previously described.

Before assembling, due to extrusion of bonding 30 material over the ridges 9, I prefer to submit the temple roll to an abrading or grinding operation to flatten said ridges on their projecting surfaces, thereby exposing the outwardly-projecting and frictional-gripping fiber ends, it being noted that 35 ridges 9 are shown in Figures 10 and 12 as being flat.

Suitable agglutinating, bonding, thermoplasticizing materials suitable for temple roll construction, have been disclosed in my inventions, Serial 40 Numbers 264,065, 249,207, 283,174, 277,608, 307,611, and 308,815, which are cited merely as several suitable materials, but the bonding material herein set forth, is to be understood as not limited to those examples or their equivalents.

45 It is essential that the bonding material used must be substantially unaffected by the fibers being woven, or materials contained therein or evolved therefrom. And conversely, the degree of adhesion, and physical characteristics of the bonding medium may be modified temporarily or 50 permanently by the use of solvents, non-solvents, softeners, flexilizers, thermoplasticizers, thermosetters and the like either in the liquid or normally solid form, a portion of which may or may not be afterwards removed, as by an evaporative 55 step. It is obvious, that if such bodies be used, they must exert no appreciable solvent or deleterious effect upon the fibers being woven, or the filaments and filatrices constituting the textile.

60 I have obtained satisfactory results by taking a ten ounce duck canvas, calendering thereon, or spreading by means of a doctor blade, or impregnating the cotton fabric until an increase in weight of around 20 to 25% of the weight of the 65 fabric has taken place. In general, it has been found that more satisfactory adhesion results, when both sides of the textile has been subjected to an adhesive and bonding composition.

In general I coat canvas of about 60 inches 70 width and in about 300 yard lengths, then cut the same into strips about three-fourths of one inch in width, where the usual form and size of temple roll is to be produced, and the bonding material possesses good flowability under heavy 75 pressure or pressure and heat.

By means of my temple roll as herein described, I obtain a double form of frictional-gripping surface, due to the alternate layers of outwardly projecting fibers or fiber ends relatively low in bonding material, and alternate layers of material 5 relatively high in thermoplasticity or thermo-setting qualities, which also possesses valuable frictional-gripping qualities, thus resulting in the formation of a temple roll of not unusually high frictional-gripping capacity, but a temple 10 roll in which that capacity remains substantially unimpaired for a long and indefinite period during use.

15 A suitable temple roll for the purposes set forth herein must show both a highly initial frictional-gripping capacity, and one which is not substantially attenuated or diminished upon long wear.

20 My temple roll as above set forth, possesses these desired qualities to a high degree, and one heretofore not attained.

What I claim is:

1. Process for roll manufacture comprising coating a textile with a suitable adhesive to which volatile solvents may be added, then cutting the coated textile into strips, piling a plurality of said strips one on top of the other pressing said pile into a firm unit if desired, slicing said pile into a plurality of strips, placing one strip above and one below on a mandrel having a removable core thereon which carries a plurality of longitudinally 30 extending fins on the same, inserting said mandrel, core and strips in a suitable split die, applying pressure thereto, finally removing the roll from the die.

2. Process for temple roll manufacture comprising calendering one or both sides of a cellulosic or non-cellulosic fabric with an agglutinant, then cutting said fabric into ribbons, piling a plurality of said ribbons one on top of another, slicing the pile into a plurality of strips, placing 40 one strip above and one below a core on a mandrel, said core having a plurality of longitudinally extending fins thereon, inserting said strips, core and mandrel in a suitable split die having internal configurations of nature desired, applying 45 heat and pressure thereto sufficient to compact the same into a homogeneously appearing body, finally removing the temple roll from the die.

3. Process for temple roll manufacture comprising impregnating canvas with suitable bonding material to which solvents may be added, then cutting said canvas into a plurality of ribbons each about three-fourths of one inch in 55 width, piling a plurality of said ribbons one on top of the other, pressing said pile into a firm unit if desired, slicing said pile on the width side into a plurality of strips, placing one strip above and one below on a mandrel containing a core said core having a roughened surface to increase adhesion thereto, said core mandrel and two strips being then inserted into a suitable split die, said die comprising a helix with spaced ridges and grooves therein, applying heat and pressure to said die sufficient to cause the two strips to assume a circular form and to meet and form a substantially indistinguishable bond, then removing the temple roll from the die and abrading the surfaces of the ridges thereof until sufficient 60 exposure of outwardly projecting, frictional-gripping ends.

4. Process for temple roll manufacture comprising calendering one or both sides of canvas with a suitable neutral thermoplastic binding material to which solvents may be added, then cutting 75

said material into strips of about three-fourths of one inch in width and of desired length, piling a plurality of said strips one on top of another, pressing said pile into a more compact unit if desired, slicing from the width of said pile a plurality of strips, placing the latter strips one above and one below a core having a plurality of longitudinally extending projections thereon said core being on a removable mandrel, inserting said core, 10 mandrel and strips in a suitable split die comprising a helix with spaced ridges and grooves therein, applying heat and pressure thereto, finally removing the temple roll from the die, removing mandrel from core, and grinding the ridges 15 thereof sufficiently to produce a flat surface thereon and expose outwardly-projecting fiber ends.

5. Process for temple roll manufacture in which the frictional-gripping textile fibers are perpendicular to the axis of the roll, comprising

cementing canvas with a suitable neutral thermoplastic bonding material, piling a plurality of pieces of treated canvas each about three-fourths of one inch in width on top of each other, compacting the pile into a firmer unit if desired, slicing said pile on the width side into a plurality of strips, laying one strip above and one below and in contact with a core on a removable mandrel inserting said core mandrel and two strips into a suitable split die, applying heat and pressure thereto until a substantially unitary-appearing mass is produced therein, finally removing the roll from the die and the mandrel from the core, and polishing off any circumferential inequalities on said temple roll surface until the 15 outwardly-projecting, frictional-gripping ends are exposed as flat ridges, as herein described and illustrated.

CHARLES THOMAS DICKEY. 20
